[57] CLAIM

The ornamental design for a planting pot clamp for suspended supports, as shown and described.

DESCRIPTION

FIG. 1 is a perspective view of a planting pot clamp for suspended supports showing my new design;
FIG. 2 is a right side elevational view thereof;
FIG. 3 is a left side elevational view thereof;
FIG. 4 is a rear elevational view thereof, rotated 90°;
FIG. 5 is a bottom plan view thereof;
FIG. 6 is a top plan view thereof.

Fig.1.

Fig.2. Fig.3.

Fig.4.

Fig.5.

Fig.6.
